UNITED STATES PATENT OFFICE.

FREDERIC C. BILLINGS, OF HARTFORD, CONNECTICUT.

DESIGN FOR A RUNNING-GEAR FRAME FOR VEHICLES.

SPECIFICATION forming part of Design No. 33,002, dated July 24, 1900.

Application filed June 18, 1900. Serial No. 20,772. Term of patent 3½ years.

To all whom it may concern:

Be it known that I, FREDERIC C. BILLINGS, a citizen of the United States, residing in Hartford, in the county of Hartford and State of Connecticut, have invented and produced a new and original Design for Running-Gear Frames for Vehicles, of which the following is a specification.

My invention relates to a design for the running-gear frames of vehicles; and it has for its object the construction of such a frame in which the front cross-bar, the side-bars or reach-rods, and the bearing-sleeves are all located in the same horizontal plane and in which a curved truss is located in line with and projects over the bearing-sleeves, said truss being connected to the rear ends of the side-bars.

In the accompanying drawing the figure 20 is a perspective view of a running-gear frame, showing my new design.

As shown in the drawing, the structure 5 of the frame is composed of side-bars or reach-rods 6, a front cross-bar 7, having end brackets 7', bearing-sleeves 8 8', located in the same plane as and projecting from the side-bars, an oblong yoke 9, uniting said bearing-sleeves, and a curved truss 10, located over but in

line with the bearing-sleeves and secured at its ends to said sleeves. Braces 12 12' connect the truss 10 to the side-bars or reach-rods, and similar braces 13 13' connect the side-bars 6 to the brackets 7 7' of the cross-bar 7. As will be observed, the side-bars or reach-rods 6 6' are arranged on tapering or 35 converging lines, and are consequently farther apart at their rear ends, where they are secured to the sleeves 8 8', than at their front ends, where they are connected to the cross-bar 7, in virtue of which the frame is made 40 more symmetrical and is better shaped to accomplish its purpose.

The leading features of my design reside in the location of the side-bars or reach-rods, the front cross-bar, and the bearing-sleeves 45 in the same plane, and in the curved truss located over said bearing-sleeves.

Having described my invention, what I claim is—

The design for a running-gear frame for vehicles, substantially as shown and described.

FREDERIC C. BILLINGS.
